CIRCUIT CONNECTION STRUCTURE

Joseph Wertzheiser, New York, N. Y., assignor
to Leviton Manufacturing Company, Brooklyn, N. Y., a corporation of New York

Application July 31, 1937, Serial No. 156,660

5 Claims. (Cl. 174—53)

This invention relates to a circuit connection structure of the class including switches, convenience outlets and similar electrical fittings.

The invention will be illustrated by reference 5 to the accompanying drawing in which

Fig. 1 is a plan view.

Fig. 2 is a side view.

Fig. 3 is an end view.

Fig. 4 is a section on the line 4—4 of Fig. 2.

10 Fig. 5 is a section on line 5—5 of Fig. 4.

Although the description and drawing relate to specific structure, there will be no limitation of the invention except as ultimately set forth in the claims, the specific description being intended merely to illustrate the invention defined by said claims, properly interpreted.

The housing has side portions 1 and end portions 2, the latter carrying circuit connection means such as binding posts or the like. The 20 unit may contain interiorly thereof any desired circuit connection means, e. g., a switch.

The unit has a body portion and a cover portion 5 and shoulder portions 6 formed at the junction of the cover and end walls. A tongue element 8 may project from each side wall and this tongue may be integrally formed in a flange 10 employed to attach the cover to the body portion. The specific manner in which the cover portion is attached to the body portion may be 30 as set forth in my copending application filed on even date herewith, Serial No. 155,355.

The unit housing is oriented and supported in the outlet box by means of a bridge member 12. This has a long and a short axis the dimension 35 along the former being sufficient to span the outlet box 14 along its long axis. The bridge member has holes 16 for attachment to suitable lugs on said outlet box and other holes 18 to permit a panel to be superimposed thereon.

40 The bridge member 12 has flange portions 20 and depending skirt portions 22. These respective portions define and encompass a centrally disposed space adapted to receive the housing unit. The flange portions 20 engage the shoulders 6 and the depending skirt portions 22 carry spring fingers 24 adapted to be sprung over and engage the tongue elements 8. The body portion of the housing may be formed of molded plastic material carrying a panel 26 raised in relief 50 thereon. The width of the panel may be slightly less than that of the tongue element 8 on the flange 10 (which is preferably metallic) and in this manner recessed parts 30 are formed at the junction of the panel and tongue whereby the 55 panel 26, tongue 8, recessed portions 30 and

spring fingers 24 by mutual inter-engagement secure the bridge member to the housing and cause the flange portions 20 thereof to bear snugly against the shoulders 6. The tongue 8 permits the spring fingers 24 to hold the shoulders 6 in engagement with the flanges 20 and the panel 26 engages the lugs 24, this mutual engagement of panel 26, spring fingers 24 and tongue 8 causing the housing to be secured within the space defined in part by the flanges 20 10 and the depending skirts 22.

I claim:

1. A circuit connection device adapted for combination with an outlet box comprising a circuit connection housing having bottom, top and side 15 portions, a bridge member having a centrally disposed space defined in part by flange members lying in a plane and engaging parts of the top portion of said housing, and in part by skirt portions in other planes, and means carried by 20 said skirt portions engaging means on the side walls of said housing to secure the housing within in said space.

2. A circuit connection device adapted for combination with an outlet box comprising a circuit connection housing having bottom, top and side portions, a bridge member having a centrally disposed space defined by flange members lying in a plane and engaging parts of the top portion of said housing, and in part by a pair of skirt 25 portions in other planes; and a pair of spring fingers carried by each of said pair of skirt portions engaging means on the side walls of said housing to secure the housing within said space.

3. A circuit connection device adapted for combination with an outlet box comprising a circuit connection housing having bottom, top and side portions, a bridge member having a centrally disposed space defined in part by flange members lying in a plane and superimposed upon and 35 engaging parts of the top portion of said housing, and in part by subjacent skirt portions in other planes; and spring fingers integral with said subjacent skirt portions engaging means on the side walls of said housing to hold said parts of the 40 top portion of the housing in engagement with said flange members and to thereby secure the housing within said space.

4. A circuit connection device adapted for combination with an outlet box comprising a circuit 50 connection housing having bottom, top and side portions said side portions carrying projections which form recessed parts; a bridge member having a centrally disposed space defined in part by flange members lying in a plane and super- 55

- imposed upon and engaging parts of the top portion of said housing, and in part by subjacent skirt portions in other planes; and spring fingers integral with said subjacent skirt portions engaging said recessed parts on the side walls of said housing and thereby holding said parts of the top portion of said housing in engagement with said flange members and securing the housing within said space.
5. A circuit connection device adapted for combination with an outlet box comprising a bridge member having a centrally disposed opening defined in part by flanges and in part by skirt por-
- 10

tions extending in a plane substantially at right angles to the plane of said flanges, a circuit connection housing adapted to be placed between said skirt portions and having a portion extending through said opening, shoulders on said housing adapted to engage with the flanges of said bridge member, and means for maintaining said shoulders in engagement with said flanges comprising spring fingers carried by said skirt portions below the plane of said flanges and means 10 on said housing adapted to engage with said spring fingers.

JOSEPH WERTZHEISER.
